UNITED STATES PATENT OFFICE.

WILBUR H. THOMPSON, OF WHEELING, WEST VIRGINIA.

MEANS FOR ATTACHING TELEGRAPHONE-CONTROL MECHANISM TO TELEPHONES.

949,690.

Specification of Letters Patent. Patented Feb. 15, 1910.

Application filed April 8, 1908. Serial No. 425,826.

To all whom it may concern:

Be it known that I, WILBUR H. THOMPSON, a citizen of the United States, residing at Wheeling, in the county of Ohio and State of West Virginia, have invented certain new and useful Improvements in Means for Attaching Telephone-Control Mechanism to Telephones, of which the following is a full, clear, and exact description.

10 This invention is an improvement in systems and apparatus for using the telephone in connection with telephone lines, whereby the operation of making a record of ordinary telephone conversation is facilitated, while the use of either the telephone or the telegraphone independently of each other, is not prevented.

15 The advantages of my invention are afforded primarily by a switching device which is attached directly to the telephone set and by means of which the various instruments and devices of the telephone and the telegraphone can be thrown into and out of use at pleasure. In another application filed by me March 2, 1908, Serial No. 418,693, I have described a method of carrying on telephone conversation and at the same time recording the speech of both parties wherein the entire voice currents are utilized at the home station to record the speech, the telephone receiver being out of circuit, and the speech of the distant party is immediately reproduced in a special receiver, from the record, to enable the home party to hear what is said to him. In the present invention, it is proposed to use the ordinary telephone receiver in listening to the record made of the distant parties speech, instead of a special telegraphone receiver.

20 This and other features of improvement, which will be fully described hereinafter, constitute my invention.

In the accompanying drawing, Figure 1 is an elevation of an ordinary telephone set having attached thereto the switching devices comprised by my invention. Fig. 2 is a conventional and diagrammatic illustration of the switching devices and the telephone and telegraphone instruments and apparatus.

An ordinary type of telephone set known as the "desk set" consists of a column on which are supported the transmitter, the receiver, and the hook switch, and I have applied my invention to such a set of instruments, although it is obviously adapted for

use in connection with other kinds of telephone sets.

Referring to the drawing, 1 indicates an ordinary telephone transmitter supported 60 upon the column 2 rising from a base 3.

4 is the ordinary telephone receiver which normally hangs upon the hook 5, which hook is arranged as usual to cut the receiver and transmitter into and out of circuit. To the 65 column 2, I attach, by means of suitable clamps 6, a switch box 7 having inside a series of movable and stationary contacts adapted to be thrown into two different combinations of connections by means of an externally arranged switch lever 8, which may be thrown into one position by hand and into the other position by the operation of the hook switch. For this purpose, a lever 9 is pivoted to the column 2 and projects at one 70 end under a tail-piece carried by the switch lever 8, and at the other end is connected by means of a link 10 with the hook switch lever. Thus, whenever the receiver is placed upon the hook 5, switch lever 8 is moved to 75 the position "T," and when the receiver 4 is removed from the hook, the switch lever is free to be moved by hand to the position "R". If the switch lever 8 is already in the position T when the receiver 4 is placed 80 upon the hook, it will not be disturbed. The usual flexible conducting cords 11 connecting with the receiver leads to certain contacts inside of the switch box 7, while another flexible cord 12 leads from other contacts inside of the box into the base 3 of the telephone set, where the usual connections with the transmitter and with the line are effected, and from the base the cord 13 to the bell and line leads. There is also proceeding 85 from the box a cable 14, containing a number of conductors leading to the telegraphone for connection with the various telegraphone magnets and with the motor. The box 7 also conveniently carries the usual 90 three push buttons 15, 16, 17, for stopping, starting and reversing the motor of the telegraphone. These are for hand manipulation and might be located anywhere in proximity to the telephone set, but for convenience are placed in the box 7. At 18 is a plug hole containing a spring jack for the insertion of a plug P which will be herein-after referred to.

Referring now to Fig. 2, the switch mechanism inside of the box 7, exclusive of that connected with the push buttons, is indicated

inside of the dotted line inclosure. 19 indicates the obliterating magnet of the telegrapher used ordinarily for the purpose of "cleaning" the recording body before it 5 passes under the influence of the recording magnet. 20 is the recording magnet which may also be used as a reproducing or listening magnet when it is not in use for recording purposes. 21 is a special reproducing or 10 listening magnet in use simultaneously with the recording magnet. 22 is a battery supplying the constant current for the obliterating magnet, and 23 to 33 respectively indicate the contacts of the switch box which are 15 affected when the switch lever 8 is moved from one position to the other.

Let it be assumed that when the telephone is to be used in the ordinary way, and no record is desired of the conversation, the switch 20 lever 8 is in the position T, and when the telephone is to be used and a record of the conversation is to be made at the same time, the switch lever 8 is to be in the position R. The 25 circuits and operation will be as follows: For ordinary telephone conversation without recording, switch 8 being in the position T, the contacts 23 to 33 will be as indicated in the drawing, the brackets *a* indicating which contacts are in connection, the others being 30 open. In this condition of the switch, the circuit of battery 22 is open for economical reasons, as there is no use for the obliterating magnet 19. The recording magnet 20 is connected in a closed circuit with a special 35 telephone receiver 34 by way of the wires 35, 36, 37, contacts 25 and 26, and wire 38. This makes it possible to use the magnet 20 as a reproducing magnet and to listen with the receiver 34 to any record that may be 40 upon the telephone, while the telephone is in use as ordinarily. This use of the telephone may or may not be taken advantage of as occasion requires; the provision is made merely for the purpose of enabling any 45 record upon the telephone to be listened to, even though the telephone is in use. The ordinary telephone receiver 4 is connected to line by way of wire 39, contacts 32 and 31, wire 40 to line and back by wire 41, contacts 50 28 and 29 and wire 42 to the receiver. An ordinary telephone conversation can therefore be carried on by using the ordinary receiver 4 and transmitter 1. In this case, the circuit of the special reproducing or listening magnet 21 is open at the contacts 30 and 55 33. Assuming the receiver 4 to be hung up after the conversation is finished, this does not disturb switch lever 8, and the connections are left in the same condition as when 60 conversing, so that at any time pending the receipt of another call, any record on the telephone can be listened to at the receiver 34 without disturbing the circuits.

When the subscriber desires to record a 65 conversation over the telephone, to which

he is a party, he throws the switch 8 by hand to the position R at the same time that he removes the receiver 4 from the hook. This shifts the connections in the box 7, the brackets *b* then indicating the closed connections, while all others are open. At the same time, one of the buttons 15, 16, 17, is pushed to start the motor of the telephone forward. The circuit of the obliterating magnet 19 is closed at 23, 24, so that 70 the recording body will be presented "clean" to the recording magnet 20. The telegrapher receiver 34 is open-circuited at the contact 25. The speech currents from the home and distant stations will come into 80 the switch box from the line 12 by wire 43, and will travel thence by wires 44 and 35 through the recording magnet 20 of the telegrapher, by wire 38, contacts 26 and 27 and wire 41 to the line. The speech of 85 both parties is therefore recorded by the telegrapher, but the currents thereof do not flow through the receiver 4, and the home subscriber does not directly hear the voice currents of the line. The reproducing 90 or listening magnet 21 of the telegrapher is, however, located immediately behind the recording magnet and reproduces the record almost instantaneously after it has been recorded. The reproduced currents will 95 flow ordinarily by wire 45, spring 46, contacts 47, (which are ordinarily closed by reason of the absence of plug P from the jack) wire 48, contacts 33 and 32, wire 39, receiver 4, wire 42, contacts 29 and 30, wire 100 49 and wire 50 to magnet 21. Thus the record on the telegrapher is heard at the receiver 4 almost instantly after it is made on the telegrapher, and the subscriber is able to carry on a connected conversation with 105 the distant party, the record being made upon the telegrapher with the full available current upon the line which yields a strong record and does not unbalance the telephone circuits.

On certain occasions when the line over which the conversation is carried, is very long, or when the transmission is poor for any reason, the record made by the telegrapher may be weaker than usual, and it is 115 desirable to use a more sensitive or loud speaking receiver than the usual telephone receiver 4 is found to be. For this reason, I have provided the spring jack and plug referred to herein, the plug P being connected 120 with the more sensitive receiver 51. The jack is located in the switch box 7 and the plug P is inserted at the opening 18. This opens the circuit of receiver 4 at contacts 47, which are separated by the insertion of the 125 plug and the receiver 51 is substituted, the circuit being as follows: From magnet 21 by wire 45, spring 52, plug P, wire 53, receiver 51, wire 54, plug P, spring 55 and wire 50. When using the sensitive receiver 130

51, the ordinary receiver 4 is simply allowed to remain off the hook, so that the connections may not be disturbed.

When the conversation is finished, receiver 4 is hung up in the usual way, and this automatically throws switch 8 from R to T, thus making it possible to use the telephone in the intervals between messages; at the same time, another of the three 10 push buttons is actuated by hand to stop the telephone motor. By adding a pair of contacts, such as indicated in dotted lines at 56 and 57, Fig. 2, the movement of the switch 8 to the position R can be utilized to 15 close the circuit of the telephone motor, thereby automatically starting the telephone at the same time that the recording circuits are put into operation.

What I claim, is:—

20 1. In a combined telephone and telegraph system, the combination of a telephone line adapted for inter-communication, a telephone, means for connecting the telephone with the telephone line for recording the telephone conversation, a telephone receiver and a switch whereby said receiver may be used at will for ordinary telephonic communication or for listening to a record of the telephone conversation.

25 2. The combination of an inter-communicating telephone system, a telephone provided with a recording and a reproducing magnet, and a switch for connecting the receiver of the inter-communicating system 30 with the reproducing magnet of the telephone.

35 3. The combination of an inter-communicating telephone system, a telephone

comprising a recording and a reproducing magnet, and switching mechanism adapted 40 to connect the recording magnet with the telephone line and the reproducing magnet with the receiver of the telephone line.

4. The combination of an inter-communicating telephone system, a telegraph, a 45 switch for connecting the telegraph to, and disconnecting it from, the telephone system, and means whereby the restoration of the telephone system to its normal condition will automatically disconnect the telephone therefrom.

5. The combination of an inter-communicating telephone system comprising a telephone receiver, a telegraph comprising another telephone receiver, and a switching 55 mechanism adapted to automatically connect the second receiver with the telegraph when the telephone system is restored to normal condition after conversation.

6. The combination of an inter-communicating telephone system comprising an ordinary telephone receiver, a telephone comprising a reproducing magnet, a sensitive or loud speaking telephone receiver, 65 and a switch whereby either the ordinary receiver or the sensitive receiver may be connected in circuit with the reproducing magnet of the telephone.

In witness whereof, I subscribe my signature, in the presence of two witnesses.
